UNITED STATES PATENT OFFICE.

JOSEPH H. HUNTER, OF DETROIT, MICHIGAN, ASSIGNOR TO DETROIT INSULATED WIRE COMPANY, OF DETROIT, MICHIGAN, A CORPORATION OF MICHIGAN.

NONSTRETCHABLE CORD.

Application filed March 20, 1922. Serial No. 545,394.

The invention relates to the manufacture of non-stretchable cords, particularly designed for use in the forming of coat hangers and for similar purposes. It is the object of the invention to obtain a construction which will not elongate under load and which will, nevertheless, be flexible and of a relatively large and substantially uniform cross section.

In the manufacture of various flexible articles, such as insulated wire, cords, etc., it is usual to use a braided covering. This braid is generally formed of yarn or cord woven around the center core and, consequently, is not only laterally flexible, but capable of a considerable degree of elongation. Where the core is metallic or formed of other relatively non-stretchable material, such a braid will serve its purpose of retaining the covering for the core while permitting lateral flexibility. On the other hand, if the core itself is fibrous or formed of a material which will stretch, the braid will not in any way prevent elongation.

It is the object of the present invention to obtain a non-stretchable cord by the use of a braid formed of relatively non-stretchable strands. Such a braid will therefore perform in addition to its usual function of enclosing the core, the additional function of preventing elongation while at the same time lateral flexibility is not interfered with. The invention therefore consists in the construction as hereinafter set forth.

In the drawings:

Figure 1 is a sectional elevation of my improved cord;

Figure 2 is an enlarged cross-section thereof;

Figures 3, 4, 5 and 6 are enlarged cross sections showing modified constructions.

The core of my improved cord may be formed of any suitable filling material, preferably strands of a fibrous nature, such as rope cotton, etc., as indicated at A. Surrounding this core there may be placed either spiral wrappings of fabric, as indicated at B, or any other material for building up the cross-section without interfering with flexibility. C is a braid surrounding the core A and wrappings B. This braid, instead of being formed of strands of fibrous material, is woven from metallic strands, preferably forming a relatively open mesh. Such a fabric, if tightly woven

about the core and wrappings, will not elongate under stress, but will permit of lateral flexing. To increase the diameter of the cord additional wrappings such as D may be placed around the metallic woven fabric C and these in turn may be enclosed in a covering E either woven or formed in any suitable manner. The completed structure will therefore be flexible, of the desired diameter and comparatively non-stretchable. Also, hangers or fastenings for the end of the cord may be securely attached thereto by anchoring to the metallic fabric.

In Figures 3 to 6 several modified constructions are illustrated. In Figure 3 the core C' is formed of a plurality of wires which may be either stranded, braided or parallel. Surrounding the core is a filler C'' which is preferably formed of jute or cotton. Surrounding the filler is a body D' of rubber compound that is preferably enclosed in a cover D'' of some suitable material such as cotton, woolen, plush, velvet or silk. In Figure 4, I have shown a core E' that is surrounded by braids of cotton E'' while surrounding the cotton E'' are a plurality of braided steel wires F'. Surrounding the wires F' are braids of cotton G' enclosed by a suitable fabric cover G''. In Figure 5 I have shown a core H which may be either wire or cord and which is enclosed within a filler H' of jute or cotton. Surrounding the filler is a body I preferably formed of braids of cotton which are enclosed by a suitable fabric cover I''. Embedded in the body I is a belt of wires I' which may be either interwoven with or between braids of the cotton. In Figure 6, I have shown a core J preferably formed of stranded wire, a filler J' of jute surrounding the core, a body K of braids of cotton surrounding the filler and enclosed within a fabric covering K''. Interwoven with or located between braids of the cotton forming the body is a belt M of wires.

What I claim as my invention is:

1. A non-stretchable, flexible cord comprising a core formed of a series of fibrous strands arranged in a substantially straight line, a fabric filler around said core for building up the cross section without interfering with flexibility, and flexible wires tightly braided with an open mesh around and embedded in the surface of said filler for preventing elongation.

2. A non-stretchable, flexible cord comprising a core formed of a series of fibrous strands arranged in a substantially straight line, a fabric filler spirally wrapped around said core for enlarging the cross section without interfering with flexibility, strands of wire tightly braided around and cutting into the surface of said filler forming a relatively open-mesh for preventing elongation of said cord under stress and permitting lateral flexing, and a covering for said strands.
3. A non-stretchable, flexible cord com-

prising a core formed of a series of fibrous strands arranged in a substantially straight line, a flexible stretchable filler around said core for enlarging the cross section, and flexible wire strands tightly braided with a relatively open mesh around and embedded in the surface of said filler for preventing elongation of said cord under stress and permitting lateral flexing.

In testimony whereof I affix my signature.

JOSEPH H. HUNTER.
